UNITED STATES PATENT OFFICE.

THOMAS I. POTTER, OF EAST ORANGE, NEW JERSEY, ASSIGNEE, BY MESNE ASSIGNMENTS, TO HYDRO REFRIGERATOR COMPANY, INC., OF NEW YORK, N. Y., A CORPORATION OF DELAWARE.

PUMP.

Application filed September 12, 1922. Serial No. 587,698.

This invention relates to improvements in pumps, particularly to a pump which is especially adapted for use as a compressor with refrigerating apparatus of the general character disclosed in co-pending application, Serial No. 500,756, filed on the fifteenth day of September, 1921.

It is a specific object of the present invention to provide a pump peculiarly adapted for automatic regulation by the braking action of the working fluid within a refrigerating apparatus, and I have shown and described a refrigerating apparatus in order that the utility of the pump for this purpose may clearly appear. It is a further object of the invention to provide a pump which is extremely unlikely to become out of order, which is hydraulically operated, and controlled by a novel type of valve mechanism.

Utilization of atmospheric pressure on the pump actuating liquid to assist in automatically stopping the pump forms a further object of the invention.

With these and other objects in view, the invention consists in certain novel features of construction, combinations and arrangement of parts as will be more fully herein-after described and pointed out in the claims.

In the accompanying drawings:

Figure 1 is a somewhat diagrammatic view principally in section through a refrigerating apparatus including my improved pump.

Figure 2 is an enlarged fragmental detail view showing the operating mechanism for the piston valve; parts being broken away and in section for clearness.

Figure 3 is another detail view taken on the line 3-3 of Figure 2.

Figure 4 is an elevational view of the operating mechanism for valve 21, and

Figure 5 is an edge view of Figure 4.

Referring in detail to the drawings, I have used the reference numeral 1 to designate a tank equipped with a rather heavy cover plate 2 which is preferably bolted as indicated at 3 to an annular external flange 4 around the upper end of the tank. An integral boss 5 surrounding an opening 6 in the cover plate provides a firm mounting

for the lower end of pump cylinder 7, wherein a weighted pump piston 8 is slidable. The piston is weighted by a relatively long 55 depending extension 9.

A cylinder head 10 for the cylinder 7 is tapped by a pair of pipes 11 and 12 leading respectively to a condenser coil 13 in the tank 1 and to a refrigerating or expansion chamber 14. A check valve 15 prevents a flow of vaporized refrigerant from the cylinder into the pipe 12 and a similar one-way valve 16 permits one-way flow from the cylinder into pipe 11.

The condenser coil 13 empties at its lower end into a reservoir 17 and an outlet pipe 18 delivers refrigerant from the reservoir to the chamber 14. The pipe 18 connects with a depending spout 19 carried by a hand-hole cover 20 forming part of the cover of the chamber 14. A float controlled valve 21 is adapted to prevent flow through the spout 19 when the level of the liquid refrigerant (preferably ethyl chloride) is 75 above a pre-determined point. The novel type of valve actuating mechanism for valve 21 will be more fully hereinafter described.

The water supply and discharge pipes designated respectively by reference characters 22 and 23 open into the tank 1 through an upwardly extending portion 24 of the cover plate casting 2. A pressure valve 25 controls the pressure of the pump actuating fluid entering through pipe 22, said 85 valve being preferably equipped with a dial such as 25' to indicate the pressure under which the pump is operated. A piston valve 26 mounted in the portion 24 of the cover plate is adapted to control the flow of 90 liquid into and from the tank. When the piston valve is in its uppermost position indicated in Figure 1, the water outlet is closed and the inlet for water under pressure is opened, whereby sufficient pressure is 95 created in the tank 1 to raise the weighted pump piston 8. As the piston valve 26 descends, it shuts off the water supply and provides communication between the tank 1 and the waste pipe 23, thereby permitting 100 the gravitationally descending pump piston to displace its own volume of water through the waste pipe.

A bifurcated lateral extension 27 at the

lower end of the piston weight 9 rides on a vertical guide rod 28 in the tank 1 and at its other side the weight 9 carries a rack bar 29. Hangers 30 depending from cover plate 2 provide mounting for a horizontal shaft 31 whereon a gear wheel 32 in mesh with the rack bar 29 is idly mounted. Sleeves 33 and 34 are fixed on opposite ends of the shaft 31 and a sleeve 35 turns freely 10 on the shaft between the gear wheel 32 and the sleeve 34.

An arm 36 on the sleeve 33 is pivotally attached to the lower end of a connecting rod 37 for reciprocating the piston valve 26. 15 A pin 38 projecting laterally from the gear 32 is adapted to engage a finger 39 on the sleeve 35 to turn said sleeve and throw a weighted arm 44 which is fixed thereto past its dead center. The sleeve 34 carries a 20 counter-balancing weighted arm 45. The arm 44 is movable between a pair of spaced laterally extending arms 46 carried by the sleeve 34 and stop lugs 47 projecting from the adjacent hanger 30 into the path of the 25 arms 46 serve to limit the rotation of sleeve 34 and consequently the shaft 31 to which it is fixed. The way in which this mechanism operates to control the piston valve will be more fully hereinafter described.

30 It is of course necessary to provide a valve operating mechanism for the valve 21 which will effectively prevent a difference in pressure between the chamber 14 and the reservoir 17 from opening the valve before the 35 level of the liquid in the chamber falls to a pre-determined point.

This result is accomplished in the following manner. A stem 48 of the valve 21 is mounted to slide vertically in the apertured 40 end of an arm 49 projecting laterally from a hanger 50 carried by the hand-hole cover 20. A link 51 pivoted on the side of the hanger is pivotally attached to the lower end of the valve stem 48. The hanger 50 at its 45 lower end provides a mounting for the pivot bolt 52 whereon a float carrying arm 53 and a weight carrying arm 54 are mounted to swing. A plate 55 swiveled on the pivot bolt is formed adjacent one edge with a cam slot 50 56 accommodating a pin 57 fixed to the lower end of the stem 48. It will then be evident that pivotal movement of the plate operates to raise and lower the valve stem and close and open the valve. Spaced lugs 58 55 on the plate 55 engage the weighted arm 54 to swing it in either direction past its dead center position. The weighted arm in swinging engages either one of a pair of lugs 59 on the plate 55 which straddle arm 54. These 60 last mentioned lugs are out of the path of the lugs 58. In other words, the float arm moves the weight arm, which in turn operates the cam to quickly open or close the valve.

65 The operation of the apparatus is as fol-

lows: The chamber 14 is almost completely filled with a suitable refrigerating liquid such as ethyl chloride. Inasmuch as the entire refrigerating operation is carried on within a closed cycle, it is preferable to exhaust the air from the chamber 14, condenser 13, pump cylinder and connecting pipes before starting operation. Assuming the pump piston to be in its lowermost position with the inlet pipe 22 in communication 75 with the tank, the valve 25 is set for the desired pressure and the tank flooded. The pressure in the tank will lift the pump piston and as the weight 9 ascends the rack 29 will turn the gear 32 operating through the 80 medium of a pin 38, arm 39, sleeves 35 and 34, shaft 31 and sleeve 33 to pull the connecting rod 37. As the connecting rod moves it pulls the piston valve downwardly shutting off the inlet pipe and opening the outlet pipe 85 just as the pump piston reaches its highest position. It will be evident that the weighted arm 44 will serve when on either side of its dead center to securely hold the piston valve in either extreme position until the 90 arm is again swung by the mechanism hereinbefore described.

As soon as the outlet pipe is opened and the intake shut off to relieve pressure in the tank the weighted pump piston will gravitationally descend reversing the operation of the gear 32 and its associated parts to lift the piston valve 26 at the proper time as will be readily understood.

The pump piston on its down stroke 100 exhausts vaporized refrigerant from the chamber 14 and on its up stroke compresses the vapor and forces it into the pipe 11 and condenser coil where the same will be condensed and delivered into the reservoir 17. The 105 volume of vapor drawn from the chamber 14 into the pump will of course always equal the volume of water displaced by the descending piston. As the temperature in the chamber 14 is gradually lowered, vaporization becomes slower and pressure in the chamber is gradually reduced. The atmospheric pressure on the water in tank 1 whenever the valve 26 is in position to open the waste pipe is of course a constant factor, 110 as is the head of water to be overcome by the descending pump piston. When the difference in pressure between the chamber 14 and the water becomes sufficiently great to 115 counterbalance the weight of the descending pump piston, the piston will be automatically stopped. This difference in pressure only occurs when the rate of vaporization in the chamber 14 is very low and the desired temperature has been reached therein. As soon 120 as the temperature in the chamber rises the rate of vaporization will increase, the difference in pressure between the chamber and tank will be lessened, the load on the pump piston relieved and the pump will again 125 130

start to operate. The head of water to be displaced by the piston in its descent also acts to supplement the load on the piston as will be readily understood.

5 Operation of the valve 26 is quite independent of pressure in the chamber 14. The valve is strictly float-controlled and will be positively opened by the weighted arm 54 falling toward the float and moving the 10 slotted plate 55 whenever the level of liquid in the tank is lowered to a predetermined point. The difference in pressure between the chamber and the reservoir 17 is sufficient to cause a replenishing flow of liquid refrigerant into the chamber whenever opening of the valve 21 takes place. As the level of the refrigerant in the chamber rises, operation of the valve mechanism is reversed and the valve closed. Weight arm 54 and float arm 15 20 53 both co-operate to prevent the difference of pressure acting on the valve from affecting its operation.

Since it will be obvious that the temperature necessary in the expansion chamber to 25 stop the pump is directly dependent upon the weight of the pump piston, means is provided in the form of attachable weights 9' for varying the weight of this piston. Cessation of operation when the temperature of 30 the material to be cooled has reached any predetermined point is thus made possible.

I have illustrated one of the preferred embodiments of the invention, but it is to be understood that various slight changes and 35 alterations might be made in the general form of the parts described without departing from the invention, and hence I do not wish to limit myself to the details set forth, but shall consider myself at liberty to make 40 such slight changes and alterations as fairly fall within the spirit and scope of the appended claims.

I claim:

1. A pump including a cylinder communicating at its lower end with a pressure chamber, a piston in the cylinder, and including an extension operable in the pressure chamber, inlet and outlet valves in the head of the piston, means for alternately introducing and relieving pressure in the pressure chamber, whereby the pump piston alternately moves upwardly in the cylinder under pressure, and downwardly in the cylinder gravitationally, and means for mechanically loading the pump piston to regulate the speed of operation of the pump.

2. A pump including a cylinder open at its lower end and having inlet and outlet ports in its upper end, a pressure chamber 50 communicating with the lower end of the cylinder, a pump piston located partly in the cylinder and partly in the chamber, means for alternately introducing and relieving pressure in the chamber, whereby the piston operates under pressure on its de-

livery stroke and gravitationally on its intake stroke, and means for mechanically loading the piston to regulate the speed thereof at any predetermined pressure of actuating fluid.

3. A pump including a cylinder open at its lower end and having inlet and outlet ports in its upper end, a pressure chamber communicating with the lower end of the cylinder, a pump piston located partly in 75 the cylinder and partly in the chamber, means for alternately introducing and relieving pressure in the chamber, whereby the piston operates upon pressure on its delivery stroke and gravitationally on its intake 80 stroke, and means for mechanically loading the piston to regulate the speed thereof at any predetermined pressure of actuating fluid, said means comprising a series of weights attachable to the piston.

4. A pump including a cylinder open at its lower end and having inlet and outlet ports in its upper end, a pressure chamber communicating with the lower end of the cylinder, a pump piston located partly in 90 the cylinder and partly in the chamber, means for alternately introducing and relieving pressure in the chamber, whereby the piston operates under pressure on its delivery stroke and gravitationally on its intake 95 stroke, and means for mechanically loading the piston to regulate the speed thereof at any predetermined pressure of actuating fluid, said means comprising a series of weights of different sizes attachable to the piston.

5. Pumping mechanism comprising a tank adapted to be filled with fluid, a cylinder opening at one end into the tank and having intake and delivery ports in its upper end, an elongated piston working in the cylinder and extending into the tank, means for alternately introducing and relieving pressure on the fluid in the tank, whereby the piston is pressure operated on its delivery stroke and gravitationally operated on its intake stroke, and a series of weight selectively attachable to the lower end of the piston for mechanically loading the same.

6. Pumping mechanism comprising a tank adapted to be filled with fluid, a cylinder opening at one end into the tank and having intake and delivery ports in its upper end, an elongated piston working in the cylinder and extending into the tank, means for alternately introducing and relieving pressure on the fluid in the tank whereby the piston is pressure operated on its delivery stroke, and gravitationally operated on its intake stroke, a guide rail in the tank, and a bifurcated lateral projection adjacent the lower end of the piston working on the guide rail.

7. Pumping mechanism comprising a tank adapted to be filled with fluid, a cylinder opening at one end into the tank and having 130

intake and delivery ports in its upper end, intake stroke, a rack secured to the piston, an elongated piston working in the cylinder valve mechanism for controlling the pressure of the fluid in the tank, and a gear ¹⁰ and extending into the tank, means for alternately introducing and relieving pressure on the fluid in the tank whereby the piston is pressure operated on its delivery stroke and gravitationally operated on its
